UNITED STATES PATENT OFFICE.

IRA H. SPENCER, OF HARTFORD, CONNECTICUT, ASSIGNOR TO THE SPENCER TURBINE CLEANER COMPANY, OF HARTFORD, CONNECTICUT, A CORPORATION OF CONNECTICUT.

CLEANING APPARATUS.

1,111,768.

Specification of Letters Patent. Patented Sept. 29, 1914.

Application filed February 20, 1907. Serial No. 358,486.

To all whom it may concern:

Be it known that I, IRA H. SPENCER, a citizen of the United States, and a resident of Hartford, in the county of Hartford and State of Connecticut, have invented a new and Improved Cleaning Apparatus, of which the following is a specification.

My invention relates more especially to the class of devices used for cleaning floors or the like, and the object of my invention is to provide a device of this class by which a floor may be thoroughly cleaned as by the application of a liquid and the surface moisture quickly removed therefrom, a single tool being so constructed that it may be used for different purposes required to accomplish such result.

A form of device in the use of which this object may be attained is illustrated in the accompanying drawings, in which—

Figure 1 is a view illustrating the manner of use and operation of my improved device. Fig. 2 is a view in elevation of the cleaner. Fig. 3 is a view in lengthwise central section through the device in a plane at right-angles to the plane of view of Fig. 2. Fig. 4 is a detail view in central section through a cleaner showing a modified form of construction.

In the accompanying drawings the numeral 6 denotes a turbine used for producing a suction and operated as by means of a motor 7. A hose or like part 8 is connected to this turbine and also with my improved cleaner. This cleaner includes a brush 9 or like scrubbing implement which may be formed in any usual manner as to the means for securing the bristles in place. This brush is preferably of considerable length as compared with its width and a pipe 10 having its outlet delivering within the bristles is arranged to convey water to the brush. A drier, also forming a part of the structure, is utilized for removing surface moisture after the brush has been used for scrubbing purposes, and water distributed upon the floor or like part in such operation. This drier consists of a mouth piece 11 having a mouth 12 through which air is drawn by the operation of the turbine 6. In the form of device herein shown for effecting this purpose I provide a head 13 to the surface of which the brush is secured, and on one edge of

which the mouth piece 11 is located. This head is preferably of considerable length, as compared with its width or depth, the mouth 12 extending practically from end to end thereof. This head has a neck 14 in which and in the head a chamber 15 is formed. This chamber 15 communicates with the mouth 12 and the pipe 10 also extends through this chamber. A soap receptacle 16 having a suitable inlet and outlet is secured to the neck and is connected with the pipes 10 and 28, a valve 32 in the construction shown herein constituting such connection. The outer walls of this receptacle are preferably water-tight, and while the inlet flow and discharge are through said pipes, other forms of construction are contemplated by me.

The neck 14 is connected with a tubular support 17 from a handle 18 to which the hose 8 is connected. This connection may be made in any suitable manner, in the form herein shown a connecting tube 14^a constituting said connection and extending into the neck 14 and into the support 17. This handle has a chamber 19 in which a valve 20 is located, closing the opening to the tubular support 17. A spring 21, in the construction shown, is employed to hold the valve to its seat, and the valve is operated as by means of a lever 22 connected with the valve stem. A delivery pipe or hose 23 extends from a source of water supply, as a stand pipe 24, to a connection 25 attached to the tubular support 17. The flow of water to the cleaner is controlled as by a valve 26. The connection 25 has an extension 27 within the tubular support 17, this extension receiving the end of a tube 28 which is connected with the soap box 16. The connections between the tubular support 17 and neck 14 or connecting tube 14^a and between the extension 27 and tube 28 are such as to allow the parts to have a turning movement one with respect to another and yet prevent leakage of air or water at the joints. Any well-known form of connection for accomplishing this result may be employed.

The use of the soap box may be dispensed with in any desired manner, and the water may be delivered directly to the brush without passing through said box 16 by connecting the tube 28 directly with the pipe 10, as

by means of the valve 32 hereinbefore described, or any other desired means for accomplishing this result may be employed.

As shown in Fig. 3 the soap box 16 extends into the chamber 15 and has formed therein a valve chamber containing a four-way valve 32 which is operated by means of a wheel 33. From the construction shown in Fig. 3 it will be readily seen that the water may be directed into the soap box and thence out through the pipe 10, or may be delivered directly through the pipes 28 and 10, the soap box in this instance being shut off.

15 In the modified form of device shown in Fig. 4 the mouth piece for removing surplus water is located within the bristles of the brush, this mouth piece 29 being secured to the head 30. The edge of the mouth piece 20 terminates in close proximity to the end of the bristles so that when it is desired to remove the water or surplus moisture a slight pressure will cause the bristles to give sufficiently to enable the mouth piece to rest upon the surface of the floor. In this form of the device a tube 34 extends along the neck 35 and into the soap box 36 into which the cleaning fluid is delivered and from which it is delivered by the pipe 31 to the bristles of 30 the brush, the valve hereinbefore described as appurtenant to the soap box to control the flow of water being omitted. The other parts of this device are the same as hereinbefore described with reference to the preferred form.

25 While my invention is shown and described herein as embodied in a certain construction, I do not limit the invention to such construction, and the invention will be 40 found to be present in various forms of construction other than is shown herein.

What I claim as my invention and desire to secure by Letters Patent is:—

45 1. A cleaner including a head containing a chamber and having a brush and a mouth piece located appurtenant one to the other thereon, said mouth piece having a mouth opening into said chamber, a neck extending from the head into a tubular support, a con-

nection on said support for attachment of an air pipe and means for supplying water to said brush.

2. A cleaner including a head, a brush located on the head, a neck extending from said head, a water supply pipe extending through said neck, a mouth piece having a mouth opening into an air chamber in said head, a tubular support to receive said neck, an extension within said support connected with the water supply, and means on said support for attachment of an air pipe.

3. A cleaner including a head with a brush secured thereto, a neck extending from said head, and having an air chamber, a water supply pipe extending within said neck and opening within the brush, a mouth piece having a mouth opening into the air chamber in the neck, a tubular support having an extension therein, said support and extension being rotatably connected with the neck and water supply pipe therein, a connection for a water supply to said support, and a connection for an air pipe to said support.

4. A cleaner including a head having a brush, means for supplying water within the brush, a suction device supported appurtenant to the brush, an extension to which the brush and suction device are secured, a valve for controlling the movement of air within said extension, a connection for a water supply pipe, and a connection for an air pipe, both connections communicating with the passage in said extension.

5. A cleaner including a head having a brush, means for delivering water within the brush, a suction device located appurtenant to the brush, an extension to which said brush and suction device are secured, a soap box mounted on the extension, said water supply extending through the soap box, means for connection of a water supply to said supply pipe, and means for connection of an air pipe to said extension.

IRA H. SPENCER.
